UNITED STATES PATENT OFFICE

146,411

DESIGN FOR A COMBINATION PROJECTOR AND SOUND REPRODUCER

Robert H. Larson, Batavia, Ill., assignor to
Operadio Manufacturing Co., St. Charles, Ill.,
a corporation of Illinois

Application May 3, 1946, Serial No. 129,279

Term of patent 7 years

(Cl. D61—1)

To all whom it may concern:

Be it known that I, Robert H. Larson, a citizen of the United States, residing at Batavia, in the county of Kane and State of Illinois, have invented a new, original, and ornamental Design for Combination Projector and Sound Reproducer, of which the following is a specification, reference being had to the accompanying drawing, forming part thereof.

Figure 1 is an elevation from one side of the combination projector and sound reproducer with the turntable and tone arm ready for use.

Figure 2 is a front elevation of the combination projector and sound reproducer with the turntable removed.

Figure 3 is a top plan view of the combination projector and sound reproducer with the tone arm in playing position on a record for illustrative purposes only.

Figure 4 is an elevation from the side opposite to that shown in Figure 1 showing the combination projector and sound reproducer.

Figure 5 is a perspective view of the combination projector and sound reproducer with the turntable disposed in a stored position and adapted for carrying in a container shown in dotted outline.

I claim:

The ornamental design for a combination projector and sound reproducer, as shown and described.

ROBERT H. LARSON.
